Attorney.

UNITED STATES PATENT OFFICE.

FOSTER RITCHIE, OF EALING, ENGLAND.

POWER-INDICATOR FOR SPRING-MOTORS.

1,381,847.

Specification of Letters Patent. Patented June 14, 1921.

Application filed January 10, 1921. Serial No. 436,080.

To all whom it may concern:

Be it known that I, FOSTER RITCHIE, a citizen of the United States of America, at present residing at 13 Florence road, Ealing, 5 in the county of Middlesex, England, have invented new and useful Improvements in Power-Indicators for Spring-Motors, of which the following is a specification.

The invention relates to a device for indicating the power of a spring or springs used to actuate motors, such for example as are used in gramophones and phonographs, and which device shows by its pointer or dial, the extent to which such a motor may 15 be used before rewinding is necessary.

It further relates to operating the device by its engagement with the existing screws usually employed in holding the spring barrels together, or by clips carrying projections attached to the spring barrels.

According to this invention a toothed wheel engages a plurality of screws one of which is rotated by the winding of the motor and the other by the unwinding thereof. 25 The turning of either screw causes the toothed wheel to rotate and to roll upon one of the screws which is stationary or which rotates at a slower speed, the latter being the case when winding and unwinding occur simultaneously.

The accompanying drawings illustrate the preferred form of the invention.

Figure 1 being a front view of the device, Fig. 2 a sectional view on the line Y—Z 35 of Fig. 1 and

Fig. 3 a front view of a modified form of operating member.

Referring to the drawings, a , a^1 are screws mounted in bearings b , b and b^1 , b^1 and carrying star or toothed wheels c , c^1 which engage screw heads or other projections from a portion of the spring drums e and e^1 . The drum e is rotated clockwise in winding the motor and in so doing causes the screw a to partly rotate, each time a projection d engages a tooth of the wheel c . The rotating of screw a which is right-handed, causes the toothed wheel w to rotate and roll in a downward direction upon the screw a^1 . 45 The projections d^1 from the drum e^1 engage in a similar manner with a star wheel c^1 , movement of which rotates wheel w in the opposite direction, resulting in a rolling upward movement, the screw a^1 being 55 left-handed. The journal v of wheel w engages with a slot in the bell-crank lever h

to allow said journal to traverse a path parallel to the axes of the screws a and a^1 . The lever h is pivoted at f and has its end g connected by a link l to the tail t of a 60 pointer which swings before a scale k , according to the vertical movement of the wheel w . Flexibility of the link l may be counteracted by the use of a spring s .

When the spring motor has no projections, such as screws d , d^1 detachable clip projections may be provided for driving the star wheel. Fig. 3 shows such a clip x constructed for clasping a motor drum a^2 and having projections d^2 , one of which may be 70 formed by one or both of the outwardly turned ends of the clip x , which ends are drawn one toward the other by the screw y .

I claim:

1. A power indicator for spring motors comprising a toothed wheel, a plurality of screw threaded members each member having a thread in mesh with teeth of the said toothed wheel, means for rotating each member, means for indicating the extent of motion of the axis of said toothed wheel in a plane parallel to the axes of said screw-threaded members, and means for supporting the parts of the device, substantially as described.

2. A power indicator for spring motors comprising a toothed wheel having an axial journal, a pair of screw-threaded members each member having a thread in mesh with teeth of the said toothed wheel and means for rotating each member, in combination with a pivoted lever arranged to be oscillated by said axial journal, means for connecting said lever with an indicator pointer and means for supporting the parts of the device, substantially as described.

3. A power indicator for spring motors comprising in combination, a toothed wheel having an axial journal, a pair of screw threaded members, each member having a 100 thread in mesh with teeth of the said toothed wheel, a star wheel fixed on each of said members and having teeth arranged for engagement by projections on a rotating part of said spring motor, a bell-crank lever having one arm slotted lengthwise for receiving the said axial journal and having its other end pierced for connection to a link, a pointer pivoted between its ends, a graduated scale parallel to the path of said 110 pointer, a link for connecting that arm of the pointer opposite its indicating end to the

pierced end of said bell-crank lever and means for supporting the parts of the device, substantially as described for the purposes specified.

- 5 4. A power indicator for spring motors comprising in combination, a toothed wheel having an axial journal, a pair of screw threaded members, each member having a thread in mesh with teeth of the said toothed
10 wheel, a star wheel fixed on each of said members and having teeth arranged for engagement by detachable clip projections secured on a rotating part of the said spring

motor, a bell-crank lever having one arm slotted lengthwise for receiving the said 15 axial journal and having its other end pierced for connection to a link, a pointer pivoted between its ends a graduated scale parallel to the path of said pointer, a link for connecting that arm of the pointer opposite its indicating end to the pierced end of said bell crank lever and means for supporting the parts of the device, substantially as described for the purposes specified. 20

FOSTER RITCHIE.
